United States Patent Office.

WILLIAM D. BAUGHN, OF MILFORD, MICHIGAN.

Letters Patent No. 69,064, dated September 24, 1867.

IMPROVEMENT IN METAL SLEIGH-KNEES.

The Schedule referred to in these Letters Patent and making part of the same.

TO WHOM IT MAY CONCERN:

Be it known that I, WILLIAM D. BAUGHN, of Milford, in the county of Oakland, in the State of Michigan, have invented an Improvement in Metal Sleigh-Knees; and I do declare that the following is an accurate description thereof, reference being had to the accompanying drawings, and to the letters of reference marked thereon, making a part of this specification.

Figure 1 represents a front view of the knee.

Figure 2 is a side view of the knee.

Figure 4 represents the top of the knee.

Figure 3 is a sectional view, cut off as at the dotted lines A B in figs. 1 and 2.

The same letters of reference are used in each of the figures.

In using this knee, which should be of cast iron, and cast with a core sufficiently large to allow a half-inch bolt to pass through it, I mortise the runner to receive the tenon D, which is protected by the water-table E. At C I lay on my beam, on top of which I place my rave; then pass a half-inch bolt from the bottom of the runner through the hole H, and through a corresponding hole bored in the beam and rave, fastened with a nut on top of the rave.

In this way I build a sleigh with no mortises and tenons except those to connect the runner and knee, and these are protected from rot by the water-table E. The knee is formed of four braces or points *a b c d* in fig. 3, which meet at a common centre.

I expressly disclaim the flanges K K.

Claim.

What I claim as my invention, and desire to secure by Letters Patent, is—

The tenon D, with the slot F, through which passes the bolt, above described.

WILLIAM D. BAUGHN.
